UNITED STATES PATENT OFFICE.

MARTIN KENNEDY, OF CHICAGO, ILLINOIS, ASSIGNOR OF ONE-HALF TO WILLIAM RENSHAW,
OF CHICAGO, ILLINOIS.

RAILWAY-CAR TRUCK.

No. 882,642.

Specification of Letters Patent. Patented March 24, 1908.

Application filed September 16, 1907. Serial No. 392,977.

To all whom it may concern:

Be it known that I, MARTIN KENNEDY, a citizen of the United States, residing at Chicago, in the county of Cook and State of Illinois, have invented certain new and useful improvements in Railway - Car Trucks, of which the following is a specification.

My invention relates to railway car trucks and has for its object to provide a truck which shall be simpler and more economical in its construction and, at the same time, stronger and more durable than the railway car trucks now in use.

There are several different kinds of trucks used in railway car construction at the present time. These trucks may be said, however, to consist in general of side members, sometimes termed arch bars, a transverse member or bolster on which the car body rests and which is elastically supported, and means for holding the arch bars in proper relation to each other and for holding the transverse member or bolster in proper relation with the arch bars. Ordinarily the side members are held in rigid, parallel relation with each other by means of a sand plank, transoms, or the like. This rigidity of structure is a disadvantage. It is evident that when the truck rounds a curve the inner and outer arch bars are subjected to different strains. A railway car truck is always, in fact, subject to very severe strains, the destructive effects of which might be lessened if the parts of the truck could be allowed a certain amount of play. In the trucks ordinarily in use to-day the arch bars are provided with openings, the bolster extending through these openings on either side. This construction obviously weakens the arch bars and, moreover, necessitates the use of means for guiding the movement of the bolster. Ordinarily the openings are made large enough not only to give play to the bolster, but also to afford space for the bolster springs, the latter being seated on the sand plank, or upon a flat surface formed on the arch bars. By thus constructing the arch bars with openings of this character, they are further weakened; and experience has shown that a large number of breaks in car trucks have occurred through the narrow portion of the arch bar near the opening. In trucks in use to-day the springs are usually seated upon a flat surface and, in consequence, they may very easily fall out or be intentionally

abstracted, or else special means has to be provided for holding them in position, which means necessitates practically the dismemberment of the trucks when a spring is broken and has to be replaced.

My invention has for its object to remedy all of these defects inherent of the trucks now in use on railway cars by providing a truck in which the number of parts shall be reduced to a minimum, the structure of these parts simplified, which shall require practically no repairs, and which shall be stronger and more durable than any now in use.

My invention has for a further object to provide means for securely holding the springs in position and which shall not be a source of weakness but, on the contrary, of strength to the truck and which shall not prevent an easy replacement of the springs in case of such necessity.

The invention has for further objects such new and improved constructions and arrangements as shall be described in the following specification and set forth more particularly in the claims.

The invention is illustrated in the accompanying drawings, in which

Figure 1 is a plan view of a truck embodying my invention with parts broken away for purposes of illustration. Fig. 2 is a vertical section on the line 2—2 of Fig. 1, looking in the direction of the arrows, a portion of the spring cup wall being broken away to show the position of the spring. Fig. 3 is an end elevation. Fig. 4 is a perspective view of the bolster. Fig. 5 is a perspective view of one of the arch bars. Fig. 6 is a vertical section taken longitudinally of the bolster; and Fig. 7 is a detail plan showing a modification.

Like characters of reference indicate the same parts in the several figures of the drawings.

The side members or arch bars are indicated by the numeral 1. Each arch bar is preferably made of a single casting. Each may be said to consist of a central, box-like structure open on the inside and top and closed on the outside by the plate 2, which forms an abutment for an end of the bolster; and extensions forward and back from the central, box-like structure for the attachment of the axle boxes. The bottom of this central, box-like structure is preferably given a cup-like formation, this construction af-

fording a secure seat for the spring or springs which sustain the bolster. In the form of device shown, two springs are to be used at each end of the bolster and hence the arch 5 bars are formed with two cups, designated by the numerals 3, 4. It will be observed that this structure is such as to reinforce the arch bar at the very point where it is subjected to the greatest strain. At the same 10 time, seats are provided for the springs which effectually prevent them from falling out, even should the truck be tipped over on one side, and which effectually removes the danger of their being intentionally abstracted. 15 The plate 2 is likewise a reinforcement to the arch bar which, it will be seen, is not weakened by any opening.

Forward and back from the central, box-like structure extend the horizontal bars or 20 pieces 5, which are preferably reinforced by diagonal braces 6 and provided with bolt holes 7 for attachment of the axle boxes. 25 The bolster consists of a beam 8, which is preferably made hollow, as shown in Figs. 4 and 6, and provided with end pieces or heads 9. These heads are adapted to be received into the box-like structure on the arch bars. 30 My invention contemplates doing away entirely with the sand plank or rigid transoms for holding the arch bars in parallel relation and accomplishing this latter by 35 means of the cross-bolster, with these manifest advantages, namely, that the number of parts of the truck is reduced and there is given to it a certain flexibility or capacity of the parts for independent movement which goes a long way toward minimizing the destructive effects of the strains to which the car truck is necessarily subjected. I accomplish 40 this result by providing an interlocking, slideable engagement between the heads of the bolster and the arch bars. Such an engagement must permit an easy, vertical movement of the bolster, keep the arch bars 45 in substantially parallel relation to each other and preferably it should allow, for the reasons above stated, a certain amount of play between the parts. Preferably I construct the heads 9 of the bolster, which I 50 prefer to make larger than the central portion of the same, on a series of offset lines, the end walls 10 of the arch bars being correspondingly formed. The box-like recesses in the arch bars have their openings on the 55 inside of the arch bars somewhat contracted. The bolster thus holds the arch bars at a proper distance and in a substantially parallel relationship. The end surfaces of the bolster are preferably given considerable 60 width, so that there are broad bearings or common surfaces of contact between the ends of the bolster and plate 2 of the arch bars.

In Fig. 7 I have shown at 11 a somewhat modified form of interlocking head, the arch 65 bar 12 being, of course, correspondingly con-

structed. It will be obvious that the precise forms given to the interlocking parts might be varied considerably.

Springs 13 are seated in the cups of the arch bar and upon these springs the bolster 70 normally is supported. The axle boxes are held in position between the ends of the arch bars and the tie bars 14 in the ordinary manner, the latter being secured to the arch bars by bolts or otherwise. The axle boxes 75 and their associated parts form no part of my invention and, therefore, have not been shown.

It will be seen that the truck is very simple both as to the number of parts and as to their structure. It may be termed a three-part truck; each part may be made of a single integral casting. Simplicity and fewness of parts are highly desirable qualities in railway construction. Obviously the fewer the parts 80 the less chance there is of breaking, and the simpler the parts the more massive and strong they may be made. It is very desirable to dispense as far as possible with small parts likely to become detached and fall under the train and with riveted and bolted joints. The arch bars of my truck present none of the elements of weakness found in the arch bars ordinarily employed at the present time; they have no openings; 85 the cup-like spring seats reinforce the structure at what is ordinarily its weakest point; the arch bars may be made of a single casting, without any riveted or bolted joints. The interlocking of the bolster with the arch 90 bars holds the latter in proper relation and still permits some slight play between the parts. The connection between the bolster and arch bars, it will be observed, is brought about without weakening the latter. If a 95 spring breaks, it is only necessary to lift the bolster, remove the broken spring and drop the new one in its place. The springs are nevertheless prevented from falling out. In case the springs should break on the road, 100 the bolster will merely settle down on the top of the spring cups and the car will be carried along as well as before, except, of course, that it will not be cushioned.

I wish it to be understood that I do not 105 desire to limit myself to the particular devices and constructions shown in the drawings, as obvious modifications will occur to those skilled in the art. Ordinarily in using my invention the members of my truck will 110 constitute the arch bars and truck bolster; for that reason I have conveniently shown and designated them as arch bars and bolster, respectively; but those terms, as used in my specification, are not intended to have 115 a limited significance, but serve to conveniently designate the end members and the transverse connecting member of my improved truck, whether, in any given embodiment of my invention, they do con- 120

stitute technically the arch bars and bolster of the structure. Obviously, also, it would be immaterial to the spirit of my invention if a greater number of elements were 5 used in a given structure.

I claim:

1. In a railway car truck, a pair of integral arch bars each consisting of a central, box-like structure open on the inside 10 and closed on the outside, with its end walls jutting inwardly in off-set planes, cups forming spring seats in the bottom of said box-like structure, horizontal bars extending forward and back from the box-like structure, 15 diagonal braces from the bottom of the box to said horizontal bars, in combination with a bolster having heads formed to correspond with the interior of the box-like structures of the arch bars so as to interlock therewith and constitute slidable engagements 20 between the bolster and the arch bars which allow free movement to the bolster and retain the arch bars at a proper distance apart and substantially parallel, and springs in said 25 cups upon which the bolster rests.

2. In a railway car truck, a pair of integral arch bars each consisting of a central, box-like structure open on the inside and closed on the outside with its end walls jutting 30 inwardly in off-set planes and the lower parts thereof having cup-like formations forming spring seats, and members extending forward and back from said box-like structure for attachment of the axle boxes, in combination 35 with a bolster having heads formed to correspond with the interior of the box-like structures of the arch bars, so as to interlock therewith and constitute slidable engagements 40 between the bolster and the arch bars which allow free movement to the bolster and retain the arch bars at a proper distance apart and substantially parallel, and springs in said cup-like formations in which the 45 bolster rests.

3. A railway truck comprising side members, a transverse member having interlocking and slidable engagement with the side members, the ends of said transverse member being inclosed by said side members, 50 which latter form abutments for the ends of the transverse member, and elastic means for supporting the transverse member.

4. A railway truck comprising side members, a transverse member having interlocking and slidable engagement with the side members, said side members having side plates against which the ends of the transverse member abut, and elastic means for supporting the transverse member.

5. A railway truck comprising side members, a transverse member having interlocking and slidable engagement with the side members, the ends of said transverse member being inclosed and guided on three sides 65 by the side members, and springs interposed

between the side members and the transverse member.

6. A railway truck comprising side members, a transverse member the ends of which abut against and slide upon the inner sides 70 of the side members, the side members formed so as to interlock with and constitute guides for the side surfaces of the transverse member, and elastic means for supporting the transverse member.

7. A railway truck comprising side members, a transverse member the ends of which abut against and have slidable engagement with the side members, and elastic means for supporting the transverse member, said side 75 members and transverse member provided with common surfaces of contact of such contour as to permit the free up and down movement of the transverse member and hold the side members at proper distance apart and 80 in substantially parallel relationship with each other.

8. The combination with a pair of arch bars each consisting of a central, box-like structure open at the inside and closed at the 90 outside, of a bolster the ends of which extend into said recesses, said bolster having interlocking and slidable engagement with the arch bars, and elastic means for supporting 95 said bolster.

9. The combination with a pair of arch bars each consisting of a central, box-like structure open at the inside and closed at the outside, of a bolster having enlarged ends 100 which extend into said recess and having an interlocking and slidable engagement with the arch bars, and elastic means for supporting said bolster.

10. The combination with a pair of arch bars each consisting of a central, box-like structure open at the inside and closed at the outside, of a bolster the ends of which extend 105 into said recesses and have flat surfaces sliding upon the flat side of the arch bars, the arch bars and bolster formed with interlocking means whereby the bolster serves to connect and hold the arch bars in proper relation, and elastic means for supporting said bolster.

11. The combination with a pair of arch bars each consisting of a central, box-like 115 structure open at the inside and closed at the outside, of a bolster the ends of which extend into said recesses and having interlocking and slidable engagement with the arch bars, cups formed in the bottom of said recesses, 120 and springs in said cups upon which the bolster is supported.

12. The combination with a pair of arch bars each consisting of a central, box-like structure open at the inside and closed at the 125 outside, with a bolster the ends of which extend into said recesses, and elastic means for supporting said bolster, the surfaces of said recesses constructed with mutually conforming, flat surfaces whereby the bolster is 130

guided in its vertical movement and the arch bars are held without the employment of other means at proper distance apart and in substantially parallel relationship with each other.

13. The combination with a pair of arch bars each consisting of a central, box-like structure open at the inside and closed at the outside, of a bolster the ends of which extend into said recesses, and elastic means for supporting the bolster, the ends of said bolster and said recesses being provided with mutually conforming surfaces of contact of such a character as without the employment of other means to maintain the arch bars in substantially parallel relationship with each other and at the same time permit a slight play between the parts so connected.

14. A railway truck arch bar consisting of a central, box-like structure open at the top and inside and closed at the outside, the lower part of said box-like structure having cup-like formation closing the boxlike structure at the bottom and part way up the inside thereof, and extensions forward and back from said box-like structure for attachment of the journal boxes, all of these parts forming a single, integral structure.

15. A railway truck comprising side members, a transverse member having interlocking and slidale engagement with the side members without extending through the same, whereby the side members are kept in substantially parallel relationship solely by means of said transverse member, the latter having capacity for vertical movement, and elastic means for supporting said transverse member.

16. A railway truck comprising side members, a transverse member having interlocking and slidale engagement with the side

members without extending through the same, whereby the transverse member has capacity for vertical movement while at the same time it holds the side members in substantially parallel relationship, but with capacity for slight independent movement.

17. A three-part railway truck comprising a pair of integral side members, an integral transverse member having interlocking and slidale engagement with the side members without extending through the same, whereby the transverse member has capacity for vertical movement freely up and down against the side members and the side members are without further means held in substantially parallel relationship with each other and means for elastically supporting the transverse member.

18. A railway truck, comprising side members and means for connecting the same, said side members being imperforate at the place of connection with said connecting means whereby the side members are held substantially parallel to each other and at a proper distance apart, but with capacity for slight independent rocking movement on the connecting means.

19. A railway truck comprising side members and a transverse member, the transverse member connecting the side members in such manner as to hold them at a proper distance and substantially parallel to each other, the side members being imperforate at the places of connection with the transverse member but with capacity for slight independent rocking movement on the transverse member.

MARTIN KENNEDY.
